US0D1078728S

(12) **United States Design Patent** (10) **Patent No.:** **US D1,078,728 S**
(45) **Date of Patent:** **** Jun. 10, 2025**

(54) **LAPTOP COMPUTER**

(71) Applicant: **Getac Technology Corporation**, New Taipei (TW)

(72) Inventor: **Shi-Liang Zhong**, Taipei (TW)

(73) Assignee: **Getac Technology Corporation**, New Taipei (TW)

(**) Term: **15 Years**

(21) Appl. No.: **29/925,357**

(22) Filed: **Jan. 24, 2024**

(51) **LOC (15) Cl.** **14-02**

(52) **U.S. Cl.**

USPC **D14/315**

(58) **Field of Classification Search**

(57) **CLAIM**

The ornamental design for a laptop computer, as shown and described.

DESCRIPTION

FIG. 1 is a top, front, and right side perspective view of a laptop computer showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the laptop computer that form no part of the claimed design.

1 Claim, 7 Drawing Sheets
